(57) **CLAIM**

The ornamental design for a hanging beverage holder, as shown and described.

DESCRIPTION

FIG. 1 is a left side perspective view of a first embodiment of a hanging beverage holder in accordance with my new design.

FIG. 2 is a front perspective view of the hanging beverage holder of FIG. 1.

FIG. 3 is a right side perspective view of the hanging beverage holder of FIG. 1.

FIG. 4 is a back perspective view of the hanging beverage holder of FIG. 1.

FIG. 5 is a bottom perspective view of the hanging beverage holder of FIG. 1.

FIG. 6 is a top perspective view of the hanging beverage holder of FIG. 1.

FIG. 7 is a top side perspective view of the hanging beverage holder of FIG. 1.

FIG. 8 is a side perspective view of the hanging beverage holder of FIG. 1.

FIG. 9 is right side view of a second embodiment of a hanging beverage holder in accordance with my new design.

FIG. 10 is a bottom view of the hanging beverage holder of FIG. 9.

FIG. 11 is a cross-sectional view of the hanging beverage holder taken along line 11-11 in FIG. 12.

FIG. 12 is a back view of the hanging beverage holder of FIG. 9; and,

FIG. 13 is a top, back-side perspective view of the hanging beverage holder of FIG. 9.

The broken lines depict portions of the hanging beverage holder that form no part of the claimed design.
